United States Patent Office.

P. S. DEVLAN, OF JERSEY CITY, NEW JERSEY, ASSIGNOR TO HIMSELF AND W. H. JEWELL, OF NEW YORK CITY.

Letters Patent No. 91,000, dated June 8, 1869.

IMPROVED LUBRICATING-CUSHION FOR RAILWAY-CAR JOURNALS.

The Schedule referred to in these Letters Patent and making part of the same.

To all whom it may concern:

Be it known that I, P. S. DEVLAN, of Jersey City, Hudson county, New Jersey, have invented a new and improved Lubricating-Cushion for Car-Journals; and I do hereby declare that the following is a full, clear, and exact description thereof, which will enable others skilled in the art to make and use the same, reference being had to the accompanying drawings, forming part of this specification, in which—

Figure 1 represents the outer end of a journal and journal-box, to which my improvement has been attached, the cap or end plate being removed.

Figure 2 is a side view of one of the lubricating-cushions, part of the covering being broken away to show the construction.

Similar letters of reference indicate corresponding parts.

My invention has for its object to furnish an improved lubricating-cushion for car-journals, which shall be simple in construction, easily put in and taken out of the journal-box, which may be washed when necessary, without injury, and returned to the journal-box, and which will absorb the oil and convey it to the journal, so as to keep the said journal constantly lubricated; and

It consists in forming the lubricating-cushion of patent elastic sponge, as hereinafter more fully described.

A represents a car-journal, and B represents the journal-box, about the construction of which parts there is nothing new.

C represents my elastic cushion, which is formed by packing the elastic sponge into two pouches made of cloth, netting, or other suitable textile material, of

which the meshes are of sufficient fineness to confine the sponge.

These pouches, bags, or covers are secured to each other at their edges, or may be formed of a single piece, so that when inserted in the journal-box beneath the journal, they may form a groove or recess to receive the said journal, as shown in figs. 1 and 2; or, if desired, the elastic sponge may be placed loosely in the journal-box. I prefer the former method, as it requires less sponge, and is very much more conveniently put into and taken out of the journal-box.

If desired, the sponge may be mixed with cotton, wool, or other suitable fibrous material, by packing the bags or covers with a thin layer of elastic sponge, then a thin layer of cotton, wool, or other fibrous material, then another layer of sponge, and so on until the said pouches or bags are filled.

These lubricating-cushions can be conveniently taken out when required, and may be washed when necessary, without in the least injuring them, and without its being necessary to remove the elastic sponge from the cover.

I claim as new, and desire to secure by Letters Patent—

A lubricating-cushion for car-journals, formed by enclosing patent elastic sponge, either alone or in alternate layers with some suitable fibrous material in a suitable textile covering, substantially as herein shown and described.

The above specification signed by me, this 10th day of March, 1869.
